UNITED STATES PATENT OFFICE.

ROBERT E. CONLIN, OF POUGHKEEPSIE, NEW YORK.

DESIGN FOR A SYRINGE-NOZZLE.

SPECIFICATION forming part of Design No. 31,465, dated August 29, 1899.

Application filed August 3, 1899. Serial No. 726,056. Term of patent 14 years.

To all whom it may concern:

Be it known that I, ROBERT E. CONLIN, a citizen of the United States, residing at Poughkeepsie, in the county of Dutchess and State 5 of New York, have invented and produced a new and original Design for a Syringe-Nozzle, of which the following is a specification.

This invention relates to a new and original design for a syringe-nozzle; and it has for its 10 object to provide a design of this character that shall be both useful and ornamental.

The leading feature of the design resides in a tubular body having rounded side portions tapering into a circular contracted neck and 15 between the planes of said rounded portions with diametrically opposite flat inclined faces converging toward the end of the body opposite said neck.

Minor features of the design are the tubular 20 body being provided with a transversely-flattened end opposite its circular neck and with a pair of spaced parallel cylindrical tubes projecting from said transversely-flattened end within the longitudinal plane of the body.

An additional minor feature of the design 25 is having the opposite flat inclined faces of a semi-elliptical shape or contour in elevation.

In the drawings, Figure 1 is a perspective view of a syringe-nozzle embodying the design 30 contemplated by the present invention. Fig. 2 is a side view thereof. Fig. 3 is a simi-

lar view in a plane at right angles to the plane of Fig. 2.

Referring to the accompanying drawings, the numeral 1 designates the tubular body of 35 the nozzle, which is provided with opposite rounded side portions 2, tapering into a circular contracted neck 3, located at one end of the body. The said body is further provided with a transversely-flattened end 4 opposite 40 the neck 3, and between the planes of the rounded side portions 2 with oppositely-located flat inclined faces 5. These inclined faces in elevation are of a semi-elliptical contour or shape and converge toward the transversely-flattened end 4 in a direction away 45 from the neck 3. To complete the design, the tubular nozzle-body is provided with a pair of spaced parallel cylindrical tubes 6, projected from the transversely-flattened end 4 within 50 the longitudinal plane of the body.

What is claimed is—

The design for a syringe - nozzle herein shown and described.

In testimony that I claim the foregoing as 55 my own I have hereto affixed my signature in the presence of two witnesses.

ROBERT E. CONLIN.
